UNITED STATES PATENT OFFICE.

LEE ANDERSON, OF PARIS, TEXAS.

CAR-COUPING.

SPECIFICATION forming part of Letters Patent No. 321,271, dated June 30, 1885.

Application filed October 30, 1884. (No model.)

To all whom it may concern:

Be it known that I, LEE ANDERSON, a citizen of the United States, residing at Paris, in the county of Lamar and State of Texas, have 5 invented certain new and useful Improvements in Car-Couplings; and I do declare the following to be a full, clear, and exact description of the invention, such as will enable others skilled in the art to which it appertains to 10 make and use the same, reference being had to the accompanying drawings, and to letters or figures of reference marked thereon, which form a part of this specification.

Figure 1 of the drawings is a vertical sectional view of my car-coupling, and Fig. 2 is 15 a top or plan view of the same.

This invention has relation to improvements in devices for coupling cars; and it is designed as an improvement upon the patent granted 20 to me June 20, 1882, No. 259,973.

These improvements consist in the construction and novel arrangement of devices, as will be hereinafter set forth, and pointed out in the 25 claim appended.

Referring to the accompanying drawings by letter, A indicates the draw-head, which is open on its upper side forwardly from the 30 pivotal point of the coupling-bar to permit a vertical movement of the same therein. The vertical lateral walls a of the draw-head are made flaring at their outer ends, and provided at their inner ends with horizontal transverse 35 perforations b, for the reception of a bolt, B, for pivoting the said coupling-bar between the jaws of the draw-head.

The coupling-bar is of a construction substantially as shown, and in outline of a contour similar to that of the coupling-bar shown in the patent referred to, having its under 40 longitudinal side somewhat arched or curved upwardly and forwardly from the pivotal point to the inner end of the hook-lugs at the forward end of the said coupling-bars. The back of the hook-head is made concave 45 from the point of its upper lug to that of its lower lug, to give greater security of connection. The lower inner walls of the draw-head

incline forwardly and downwardly from its rise c, which is below and forward of the pivotal point of the coupling-bar. By this construction it will be seen that the connecting-bar will be permitted to drop below a horizontal plane to engage a coupling-bar of a car of less height, and will at the same time be held up above the front of the floor Z sufficiently to admit the coupling of the opposite car. The draw-head A is also provided on its under side, beneath the pivotal point of the coupling-bar, with a vertical recess, C, for the passage of an operating-lever, D, attached to 50 the rear end of the said connecting-bar, the upper end of the bar being longitudinally recessed, as shown at d, for the reception of the forward end of the said lever, which is secured thereto by screws or other suitable fastening 55 devices. This operating-lever, connected to the rear end of the coupling-bar, extends downward through the recess in the draw-head, and then turning extends rearwardly beneath the draw-head to within convenient reach of 60 the operator or brakeman. The rear vertical wall, e, of the draw-head is also provided with an under vertical recess, E, forming a receptacle for the bend of the lever.

From the foregoing description, taken in 65 connection with the accompanying drawings, the operation and advantages of my invention will be obvious.

Having thus described my invention, what I claim as new, and desire to secure by Letters Patent, is—

The combination, with the draw-head having the downwardly and forwardly inclined floor Z and the floor slot or opening, of the coupling-bar having a curved or angular lever 85 secured to its rear end and extending first downward through said opening and then under the draw-head, substantially as specified.

In testimony whereof I affix my signature in presence of two witnesses.

LEE ANDERSON.
